(57) CLAIM

The ornamental design for a two-handled mug, as shown and described.

DESCRIPTION

FIG. 1 is a perspective view of a two-handled mug showing my new design;

FIG. 2 is a top plan view thereof;

FIG. 3 is a front elevation view thereof;

FIG. 4 is a right side elevation view thereof, the left side elevation being a mirror image of the right side;

FIG. 5 is a rear elevation view thereof; and,

FIG. 6 is a bottom plan view thereof.
